CARRIAGE STROKE MECHANISM FOR SLICING MACHINES

Otto Theurer, Brooklyn, N. Y., assignor to Edward I. Friedman, New York, N. Y., and Harry Wiener, Brooklyn, N. Y.

Application June 12, 1936, Serial No. 84,807

8 Claims. (Cl. 74—44)

The present invention relates to mechanisms for translating a rotary motion into a reciprocatory motion, particularly for reciprocating a carriage on a frame and of a type adapted for embodiment in food slicing machines as a carriage stroke mechanism.

The principal object of this invention is to provide a novel and improved mechanism of the character described which is exceptionally compact in construction and which has a new mode of operation.

Another object is to provide a mechanism of the type mentioned wherein the arena of action of its moving parts requires but about half the space necessitated by reciprocating mechanisms of the class employing an ordinary crank and connecting rod assembly.

To attain these objects, and others which will become manifest as the disclosure proceeds, in an embodiment of this invention, I provide a driving shaft journalled in position normal to the path of travel of the carriage, and an extensible mechanism driven therefrom, which first becomes extended and then collapsed or folded to one side of the axis of the shaft and then to the other side thereof, which operation alternately repeated will cause the carriage to travel back and forth.

This invention is capable of numerous forms and various applications without departing from the essential features herein disclosed. It is therefore intended and desired that the embodiment shown herein be deemed illustrative and not restrictive, and that the patent shall cover whatever features of patentable novelty exist in the invention disclosed; reference being had to the appended claims rather than to the specific description herein to indicate the scope of the invention.

In the accompanying drawings forming part of this application, similar characters of reference indicate corresponding parts in all the views.

Fig. 1 is a plan view of a slicing machine construction, embodying the present invention, showing the carriage at one end of its stroke or travel.

Fig. 2 is a reduced section taken at line 2—2 in Fig. 1.

Figs. 3 and 4 are views similar to Fig. 1, showing a diagrammatic representation of the relative positions of parts of the mechanism, at intermediate positions of the carriage along its line of travel.

Fig. 5 is a similar view showing the carriage at its other remote position.

Fig. 6 is a fragmentary view showing a modified construction of the manner of connecting the carriage with the reciprocating mechanism structure.

In the drawings, the numeral 15, is used to designate generally the base frame of a slicing machine and the numeral 16, a carriage slidably mounted thereon along the horizontal track mem-

bers 17 and 18. Within the frame, is journalled a horizontally positioned drive shaft 19, provided with a hand wheel 20, at its forward exteriorly extending end, a bevel gear 22 at its other end interior the case or frame 15, and another bevel gear 21 at the bearing 23. The usual circular knife 24, pivotally mounted so that its plane is parallel to the line of travel of the carriage 16, is revolved by a system of sprockets 25 and 26 carrying the chain 27, which receives motion by means of gear 28 in engagement with the gear 22.

The bevel gear 21, is in engagement with gear 29, to drive a shaft 30, which is vertically positioned through the base frame 15, and extends upward thereof, upon which external portion is securely mounted a gear 31 and a collar 32, between which is a loosely mounted link 33. Loosely mounted through the link 33, is a pin 34, which carries secured at its lower end a gear 35 in engagement with the aforesaid gear 31, and secured at its upper end is the link or crank 36 at an end of the latter, which has integrally extending therefrom the cam follower element 37. The crank 36, at its pin 38, is linked to the end of another link designated as 39, which itself is pivotally secured at 40 to the carriage 16, and permitted to be oscillated between the spaced stops 41 and 42 secured to the carriage or integral with the latter to extend in the path of travel of said member 39. As an alternative construction, the crank 36, at its pin end 38 may be linked pivotally to block 43, which is free to oscillate along rod 44 between said stops 41 and 42.

For further reference herein to facilitate explanation, 30, 34, 38 and 40, may be deemed points, in the plan views in the drawings. When the carriage 16, is at either end of its stroke, these points are colinear. On a line perpendicular thereto, at opposite sides of point 30, and equally spaced therefrom, there are secured to the frame 15, the cam members 45 and 46 respectively, for the guidance of the cam follower 37, when the latter reaches their respective vicinities.

In operation, upon rotating the hand wheel 20, it is evident that the knife 24 will revolve, as also will shaft 30, and the pin 34; the latter about its own axis travelling in a circle having point 30 as the centre of its path. The links 33 and 36 will be moved to fold whereby they set one over the other, and point 38 will approach point 30, whereby the carriage 16 will be slid along the track members 17 and 18 to the line of the cam members 45 and 46, and the cam follower 37, will contact the cam member 45. The lines defined by points 34, 38, and by points 34, 30, will next coincide. It is necessary at this time that said coinciding lines assume an angular relation increasing in the direction of carriage travel. Since point 34 will continue to move about 30, the action of the cam 45 will accomplish the required 60

unfolding of the links 33 and 36, and the carriage will continue after these stages, as illustrated in Figs. 3 and 4, to the remote end of its travel at the other side of point 30, as shown in Fig. 5. 5 Upon continued rotation of the hand wheel 20, the carriage 16, will be slid back to its initial position, and the unfolding of the links 33 and 36, will occur this time at the cam member 46. The cycle is then repeated as many times as required. 10 The mechanism herein set forth is especially compact and permits the building of slicing machines which require but small space, and is adaptable for embodiment in many types of machines and devices which include particularly reciprocating carriages, or components requiring similar motions as are accomplished by the present invention.

Simultaneously herewith, I have filed a companion application for patent to cover a Cross feed mechanism for slicing machines, wherein I describe means related to the subject matter herein to accomplish an intermittent sliding movement of a platform on the carriage, whereby the substance to be sliced is advanced periodically to a position forward of the plane of the knife, prior to the commencement of each cycle of movement of the carriage 16 herein.

Having fully disclosed a preferred embodiment of my present invention as herein described, I 30 claim:—

1. In combination, a frame, a carriage slidably mounted thereon, an extensible means connected at its ends to the carriage and frame respectively, and means to extend and collapse said extensible means at either side of its point of connection with the frame successively, whereby the carriage passes such point of connection, and is reciprocated.

2. In combination, a frame, a carriage slidably mounted thereon, an extensible means linked at its ends to the carriage and frame respectively, and means to extend and collapse said extensible means to one side of its point of connection with the frame, then turn said extensible means and 45 extend and collapse same at the other side of said point of connection, whereby the carriage passes such point of connection, and is reciprocated.

3. In combination, a frame, a carriage slidably mounted thereon, an extensible means connected 50 at its ends to the carriage and frame respectively, means to extend and collapse said extensible means successively, and means to reverse the direction of extension of the extensible means, whereby the carriage passes the point where the 55 extensible means is connected to the frame, and is reciprocated.

4. In combination, a frame, a carriage slidably mounted thereon, provided with a pair of stops spaced along a line transverse its line of motion, 60 a member mounted on the carriage, moveable between said stops, a pair of foldably secured links mounted pivotally at the end of one to the moveable member on the carriage, and pivotally at the end of the other to the frame, a shaft journaled 65 in the frame, means carried by the links and driven by the shaft, adapted to unfold and fold the links at either side of the link pivot on the frame successively, upon rotation of the shaft, and means to revolve the shaft, whereupon the 70 carriage is reciprocated.

5. In combination, a frame, a carriage slidably mounted thereon, provided with a pair of stops spaced along a line transverse its line of motion, 5 a member mounted on the carriage, moveable between said stops, a pair of pivotally secured links mounted pivotally at the end of one to the moveable member on the carriage, and pivotally at the end of the other to the frame, and means adapted to revolve the first link about the axis at the juncture of the pair of links and simultaneously revolve said axis about the point of pivotal connection of the second link with the base, whereby the carriage is reciprocated.

6. In combination, a frame, a carriage slidably mounted thereon, provided with a pair of stops 15 spaced along a line transverse the line of its travel, a member mounted on the carriage moveable between said stops, a shaft rotatably mounted in the frame, normal to the line of travel of the carriage, a pair of pivotally secured links mounted pivotally at the end of one to the moveable member on the carriage, and at the end of the other, pivotally about the shaft as an axis, a gear secured on the shaft, a second gear secured with the first link about the axis at the juncture of the 20 links; both gears being in engagement, means to unfold the links mounted at each side of the frame, and means to rotate the shaft, 25 whereupon the carriage is reciprocated.

7. In combination, a frame, a carriage slidably mounted thereon, provided with a pair of stops spaced along a line transverse the line of its travel, 30 a member mounted on the carriage moveable between said stops, a shaft rotatably mounted in the frame, normal to the line of travel of the carriage, a pair of pivotally secured links mounted pivotally at the end of one to the moveable member on the carriage, and at the end of the second, pivotally about the shaft as an axis, a gear secured on the shaft, a secured gear secured with the first link about the axis at the juncture of the 35 links; both gears being in engagement, means positioned on the frame at either side of the first gear, adapted to intercept the end of the first link and turn it slightly about the juncture of the 40 links as an axis, and means to rotate the shaft, 45 whereupon the carriage is reciprocated.

8. In combination, a frame, a carriage slidably mounted thereon, provided with a pair of stops spaced along a line transverse the line of its 50 travel, a member mounted on the carriage moveable between said stops, a shaft rotatably mounted in the frame, normal to the line of travel of the carriage, a link provided with a cam follower element projecting therefrom at one end, a 55 second link pivotally secured to the first link at that end; the other end of the first link being pivotally secured to the moveable member on the carriage, and the other end of the second link being pivotally mounted about the shaft as an 60 axis, a gear secured on the shaft, a second gear secured with the first link about the axis at the juncture of the links; both gears being in engagement, cam means positioned on the frame at either side of the first gear, adapted to turn 65 the first link about the juncture of the links as an axis upon contact with the cam follower, and means to rotate the shaft, whereupon the carriage is reciprocated.
